Edgar Dale & Co.

UNITED STATES PATENT OFFICE.

DAVID WEISSMAN, OF BROOKLYN, AND LEISER REISER, OF NEW YORK, N. Y.

SAFETY POCKET-LOCK.

1,266,893.

Specification of Letters Patent. Patented May 21, 1918.

Application filed January 16, 1917. Serial No. 142,617.

To all whom it may concern:

Be it known that we, DAVID WEISSMAN and LEISER REISER, respectively a subject of the Czar of Russia and a citizen of the 5 United States, and residing, respectively, at Brooklyn, in the county of Kings and State of New York, and New York, in the county of New York and State of New York, have invented certain new and useful Improvements 10 in Safety Pocket-Locks, of which the following is a specification, such as will enable those skilled in the art to which it appertains to make and use the same.

This invention relates to devices for locking the change or money pocket of a garment or a container of any kind or class in which valuables are carried, and the object thereof is to provide a device of this class which is simple in construction and operation and efficient in use and which will not interfere with the use of the pocket or other container.

The invention is fully disclosed in the following specification, of which the accompanying drawing forms a part, in which the separate parts of our improvement are designated by suitable reference characters in each of the views, and in which:—

Figure 1 is a side view of the top portion 30 of a pair of trousers indicating the side pocket thereof in an open position and showing our invention applied thereto;

Fig. 2 a central longitudinal section through the separate parts of our improved lock device showing the same in their operative or closed position and indicating the garment;

Fig. 3 a transverse section on the line 3—3 of Fig. 2 and on an enlarged scale;

Fig. 4 a transverse section on the line 4—4 of Fig. 2 on an enlarged scale;

Fig. 5 a back view of one of the separate parts of our improved lock device detached;

Fig. 6 a back view of the other part of 45 our improved lock device detached;

Fig. 7 a view similar to Fig. 3 but showing only a part of the construction and showing a modification;

Fig. 8 a view similar to Fig. 6 but showing a modification; and,

Fig. 9 a transverse section on the line 9—9 of Fig. 8 and showing the method of attaching the separate parts of the lock device, as shown in Fig. 8, to a garment.

55 In Fig. 1 of the drawing, we have indi-

cated at *a* the top side portion of a pair of trousers having the usual side pocket *a*², consisting of a back portion *a*³ and a front portion *a*⁴.

In the practice of our invention, we employ a lock device *b* consisting of two oblong sheet metal plates *c* and *d*, the plate *c* being provided with a central longitudinal and hollow cylindrical portion *c*² which extends approximately the full length of said plate 60 and is made up of separate parts *c*³ and *c*⁴ secured together by welding or in any other desired manner. The part *c*³ forming a convex back member, while the part *c*⁴ forms a convex front member. 70

The plate *d* is provided with a central longitudinal concavo-convex portion *d*² which extends approximately the full length of said plate and is adapted to receive the front convex portion *c*⁴ of the plate *c* when the 75 separate parts are placed together.

Mounted in the cylindrical portion *c*² of the plate *c* is an L-shaped block *e* having a rod *e*² connected therewith, said rod extending through one end of the cylindrical portion *c*² and being provided with a ring or eye *e*³ with which when the device is in use is connected a chain, cord or tape *e*⁴, which is also connected with a button or other device *f*, as indicated in Fig. 1, and 85 mounted on the rod *e*² between the head *e* and the end of the cylindrical portion *c*² is a coil spring *g* which serves to move said block *e* inwardly, the extent of this movement being limited by a stop *e*⁵ on the rod *e* 90 as shown in Fig. 2.

Mounted centrally of the convex portion of the plate *d* is an L-shaped dog *h* which is adapted to operate in connection with the L-shaped block *e*, in the cylindrical portion 95 *c*² of the plate *c*, and said block serves to lock the dog in the position shown in Fig. 2 against outward movement and to lock the separate plates *c* and *d* together, as will be readily understood. 100

As shown in Figs. 1 to 6 inclusive, the plates *c* and *d* are secured to the separate parts *a*³ and *a*⁴ of the pocket by U-shaped pins *i* and *j*. The pin *i* serving to secure the plate *c* to the part *a*³ of the pocket by passing 105 it through the material of said part and through apertures *c*⁵ formed in ears *c*⁶ on the end portions of said plate; while the plate *d* is secured to the part *a*⁴ of the pocket by passing the pin *j* through the material 110

of said part and through apertures d^3 formed in ears d^4 on the end portions of the plate d .

When the separate parts are secured in position as above set out, the chain, cord or tape e^4 is connected with the button f which may be secured at any convenient place in the top portion of the trousers, or other garment, and when the separate parts are secured together, as shown in Fig. 2, to close the pocket, the pocket may be opened by pulling on the chain or cord e^4 to release the L-shaped block e from the dog h , and again closed by snapping or pressing the separate parts or plates c and d together, the dog h operating to move the L-shaped block e against the tension of the spring g in this last operation.

When the separate parts c and d are secured together by the locking members, the concave portion d^2 will embrace the tubular portion c^2 and thus the parts will be prevented from turning or moving relative to one another. By reason of this construction the pocket will be tightly closed throughout substantially its entire length and there will be no open spaces between the tubular portion c^2 and concave portion d^2 .

Instead of securing the plates c and d to the separate parts of the pocket by the pins i and j , which form a detachable connection, the same may be secured thereto by stitching for which purpose I provide the edge portions of the separate plates c and d with a plurality of apertures c^7 and d^5 through which the thread k for stitching said plates to the garment passes, as clearly indicated in Fig. 7, in which figure the plate d is shown secured to the garment.

In Fig. 8 of the drawing, we have shown another modified form of securing the plates c and d to the garment which consists in providing the edge portions of said plates with a plurality of prongs or projections m , and in said figure we have shown said prongs or projections on the plate d . In the operation of attaching the plates with the prongs or projections m thereon to the garment, said prongs or projections are first bent at right angles to the plates and forced through the garment and bent inwardly as shown at m^2 in Fig. 9 to grasp the garment between the same and the side portion of the plates and in this way the plates are permanently secured to the garment and held against any possible movement, or against detachment therefrom.

While we have shown our improvement applied to the side pocket of a pair of trousers it will be understood that the same may be used in connection with pockets of any kind or class of garments as well as in connection with containers of various kinds

and classes, such as pocketbooks, bags and the like, the gist of our invention being a lock device composed of separate parts and lock mechanism in said parts controlled by a device known to the owner or user only, and various changes in and modifications of the details of construction herein shown and described may be made, within the scope of the appended claims, without departing from the spirit of our invention or sacrificing its advantages.

It will be noted that the front part c^4 of the cylindrical portion c^2 of the plate c is provided with a central oblong aperture c^8 through which the dog h passes as will be readily understood.

Having fully described our invention, what we claim as new and desire to secure by Letters Patent, is:—

1. A safety pocket lock comprising two independent oblong sheet metal parts adapted to be secured to the opposite walls of the pocket of a garment, one of said parts being provided with a longitudinal tubular portion in which is mounted a longitudinally movable spring-controlled lock device and the other part being provided with a longitudinal concavo-convex portion adapted to engage the tubular portion for preventing relative movement of the parts and having a lock device engaging member adapted to be passed into said longitudinal tubular portion and to engage the lock device therein, said lock device being provided with a part which passes outwardly through one end of the said longitudinal tubular portion and is movable therethrough and which is also adapted to be passed outwardly through one part of the pocket.

2. A safety pocket lock, comprising two independent parts adapted to be secured to the opposite walls of the pocket of a garment, one of said parts being provided with a convex portion extending substantially the entire length of said part and provided with a locking member, and the other part being provided with a longitudinally disposed concave portion adapted to engage the convex portion of the other part for preventing relative movement of the parts, and a locking member provided on the concave portion adapted to coöperate with the locking member of the convex portion for closing said pocket.

In testimony that we claim the foregoing as our invention we have signed our names in presence of the subscribing witnesses this 13th day of January, 1917.

DAVID WEISSMAN.
LEISER REISER.
